UNITED STATES PATENT OFFICE

167,587

GENTLEMAN'S CHIFFONIER OR SIMILAR ARTICLE

Frank A. Pierce, Florence, Ala.

Application March 9, 1950, Serial No. 8,443

Term of patent 14 years

(Cl. D33—6)

To all whom it may concern:

Be it known that I, Frank A. Pierce, a citizen of the United States, residing at Florence, in the county of Lauderdale and the State of Alabama, have invented a new, original, and ornamental Design for a Gentleman's Chiffonier or Similar Article, of which the following is the specification, reference being had to the accompanying drawing, forming a part hereof.

Fig. 1 is a front elevation of a gentleman's chiffonier or similar article embodying my new design;

Fig. 2 is a cross sectional view thereof taken on line 2—2 of Fig. 1.

Fig. 3 is a fragmentary, enlarged perspective view thereof, showing a portion of two center shelves.

The characteristic features of my design reside in the portions shown in full lines.

I claim:

The ornamental design for a gentleman's chiffonier or similar article, substantially as shown and described.

FRANK A. PIERCE.
